UNITED STATES PATENT OFFICE.

HENRY D. GORTNER, OF COLORADO SPRINGS, COLORADO.

ELECTRICAL PENDANT SWITCH.

1,029,750.

Specification of Letters Patent. Patented June 18, 1912.

Application filed July 12, 1911. Serial No. 638,097.

To all whom it may concern:

Be it known that I, HENRY D. GORTNER, a citizen of the United States, residing at Colorado Springs, in the county of El Paso and State of Colorado, have invented certain new and useful Improvements in Electrical Pendant Switches, of which the following is a specification, reference being had to the accompanying drawings.

10 This invention relates to switches for opening electrical circuits, and more particularly to that class of switches that are known as pendant switches.

15 The objects of this invention are to provide a pendant switch which can be manufactured at a comparatively low cost, to have a relatively small number of parts, and to have such parts rigidly mounted within the switch, to have a switch body proper of 20 symmetrical design which can be readily and cheaply manufactured, to have the sections of said switch connectible together by means which eliminate the necessity of screws, or other devices that necessitate the 25 use of tools, to eliminate the use of springs that have the liability of getting out of order, to have only one movable part within the switch, this part being the push button itself, which through necessity must move 30 within the switch, to have all the parts arranged so that they can be replaced, should it be necessary to do so, to bring the designs of the parts to such a minimum number that the cost of manufacture may be greatly reduced, to provide a switch which can be 35 readily assembled by unskilled labor, to provide a switch which will not necessitate the use of tools in its assembling, to provide a switch which will withstand a rough usage 40 and continuous wear for a comparatively long time, to have a switch which it will be practically impossible to short circuit, to provide a switch which will meet all the requirements met with in practice, and at the 45 same time, will be ornamental, perfectly insulated and exceptionally low in cost to manufacture.

This invention is simple in every way and the body proper is in two symmetrical

halves. There are four posts of similar design, two of which are arranged to receive circuit wires and all four arranged to form the means whereby the shell parts are held securely together. The means for making the contact consists of a flat strip of metal 55 which is suitably bent to resiliently engage with the push rod of the switch, so that, when the push rod is moved from one position to the other, it will raise or lower, as the case may be, the flat piece of metal and 60 put it into contact with the other post connected to the other side of the line, and thereby complete the circuit. This arrangement makes it possible to manipulate this switch for a considerable time, because there 65 is no possibility of any of the parts becoming disarranged, or otherwise getting out of order. They are only capable of being worn by the frictional action on which their action depends. This wear will take a considerable time to produce any noticeable effect in the parts so that an exceptionally long life is given to the switch.

In the accompanying drawings which illustrate by way of example an embodiment of this invention: Figure 1 represents a pendant switch embodying this invention; Fig. 2 represents an interior view of the switch with one half of its shell removed; Fig. 3 is a detail of the push rod used in 80 this invention; Fig. 4 is a detail showing the interior of one half of the shell; Fig. 5 is a central sectional view of the switch.

Similar reference characters refer to similar parts throughout the drawings. 85

In the construction shown in the drawings 1 represents one of the halves of the shell body proper. Each half is symmetrical with the other.

2 is a recess provided in the shell 1 in order to permit the insertion of a push rod 3 therein, and also to provide means for connecting screws 4 which are secured to the posts or dowels 5 and 6 to be disposed therein. The plate 7 is made of a flat piece of 90 material secured to one of the binding screws 4 so that it will be held securely in 95 position so that it will come in engagement

with the push rod. A hump 8 is provided on the upper portion of the push rod 3 and in the middle portion thereof, so that when the push rod is actuated this hump will 5 press the plate 7 up against the other binding post so that the circuit will be completed. When it is desired to open the switch the push rod is pushed back in the ordinary way, so that the hump moves out of engagement with the plate and permits the 10 same to open the circuit.

The posts 5 and 6 extend from the shell they are in so that they will engage in the holes 9 and 10 in the other shell. These 15 posts are shaped so as to fit closely therein and frictionally prevent the shell portion from coming apart after the same are put together until it is purposely intended to separate them, in which case it will be necessary to use quite a little force to disengage the shells from these posts. Posts 11 and 12 are mounted on the opposite portion of the same shell in which the first mentioned posts are normally secured, in order 20 to provide means whereby the shell portions will be held more securely together, being arranged to fit in the same manner into corresponding holes 13 and 14 in the other shell portion, which can be readily seen from the 25 drawings.

Should it appear desirable, the posts or dowels 5 and 6 and 11 and 12 are preferably additionally held in the lower shell by means of a suitable glue or cement, while 30 the upper portions of these posts are arranged to fit in their respective holes and only frictionally be held therein. This friction will in most cases be sufficient to hold these parts firmly and securely together.

40 Provided in the upper portion of the shells are the grooves 15 and 16 which come together when the shells are closed on one another, and form a hole for the wires that go to the switch. The inner portion 2 in the shells are arranged to permit the wires for the switch to be disposed therein, in the usual manner. Enough space is left therein to provide for the usual knot put on the wires or any other arrangement usually practised.

45 From the above description the operation of the device is apparent, and its convenience will be readily appreciated by those skilled in the art.

Obviously, while there is shown but one 55 modification of the construction of this invention, in the drawings, it is not desired to limit this application for a patent in any way, otherwise than necessitated by the prior art, as many modifications of the construction of this invention may be made, without departing from the principles thereof. It is also understood that the frictional securing means described, can be used

for electrical apparatuses of a kindred nature such as sockets, etc.

Having thus described this invention it is claimed:

1. A switch comprising a body proper, consisting of a plurality of sections, said sections being of a similar form and provided with a plurality of recesses therein, a plurality of posts frictionally held in corresponding recesses in said sections to hold the sections together, binding screws disposed on some of said posts and arranged to take the circuit wires and a plate for making contact between the last mentioned posts, and means for moving said plate into contact with said latter posts.

2. A switch comprising a body consisting of mating sections provided with recesses, dowels disposed frictionally in said recesses and adapted to hold the sections together, binding posts mounted on sundry of said dowels and arranged for the attachment of the circuit wires thereto, a plate secured to one of said posts and arranged for making contact between the posts, and a push rod movable in said sections and arranged to push said plate in a direction to make contact between the posts.

3. A pendant switch comprising a body proper, consisting of a plurality of sections, said sections having a plurality of recesses therein, a plurality of posts, said posts being disposed in recesses in adjacent sections so as to hold said sections frictionally together, means disposed on some of said posts for electrically connecting circuit wires thereto, a member connected to one of said last mentioned posts, and means for moving said member into contact with another of the last mentioned posts.

4. A switch comprising a body proper having a plurality of symmetrical sections, said sections being provided with a plurality of recesses therein, a plurality of posts disposed in the recesses of adjacent sections so that the same will be held frictionally together, means for securing circuit wires to said posts, and means for electrically connecting said posts together.

5. A switch comprising a body proper having a plurality of sections, said sections being provided with a plurality of recesses therein, a plurality of posts disposed in the recesses of adjacent sections, binding screws disposed on a pair of said posts and arranged to secure circuit wires thereto, and a member for making electrical contact with the last mentioned posts, and means for causing said member to make contact with the last mentioned posts.

6. A switch of the character described, including a sectional body, the sections of which are formed with recessed portions,

dowels frictionally engaged in said recessed portions of the respective sections, whereby to hold the sections of the body together, binding posts mounted on said dowels, a 5 spring plate secured to one binding post and normally disengaged from the other post and a push rod movable through the body and provided with a raised portion adapted to engage the relatively free end

of said plate and to move the same in a direction to complete the circuit.

In testimony whereof I hereunto affix my signature in the presence of two witnesses.

HENRY D. GORTNER.
